(57) **CLAIM**

The ornamental design for a wall of an escalator, moving walkway, elevator or lifting apparatus, as shown and described.

DESCRIPTION

The sole FIGURE is a front view of a wall of an escalator, moving walkway, elevator or lifting apparatus.

The broken line surrounding the wall of an escalator, moving walkway, elevator or lifting apparatus depicts the boundaries of the claim and forms no part thereof. The article is flat. Depth forms no part of the claimed design.

The portion of a wall of an escalator, moving walkway, elevator, or lifting apparatus is flat and planar. Depth forms no part of the claimed design.

1 Claim, 1 Drawing Sheet
